UNITED STATES PATENT OFFICE.

MAX E. HERTWIG, OF ELIZABETH, NEW JERSEY.

SHADE-SUPPORT.

1,130,973.

Specification of Letters Patent.

Patented Mar. 9, 1915.

Application filed July 11, 1913. Serial No. 778,605.

To all whom it may concern:

Be it known that I, MAX E. HERTWIG, a citizen of the United States, residing at Elizabeth, in the county of Union and State 5 of New Jersey, have invented certain new and useful Improvements in Shade-Supports; and I do hereby declare the following to be a full, clear, and exact description of the invention, such as will enable others 10 skilled in the art to which it appertains to make and use the same.

This invention relates to new and useful improvements in shade brackets and has for its object the provision of a device of the 15 above character which may be easily and quickly attached to a window frame without the use of screws or other separate fastening means.

Another object of my invention is the 20 provision of such a device which may be adjusted to receive different lengths of shade rollers without necessitating the removal of the same from its position on the window frame.

25 Still another object of my invention is the provision of such a device which will be simple in operation, cheap in construction and effective in use.

With the above and other objects in view 30 I will now proceed to describe my invention in the following specification and accompanying drawings, in which,

Figure 1 is a view of the window showing my improved shade support in position 35 thereon, Fig. 2 is an enlarged detail end view of my improved shade support, and Fig. 3 is a detail perspective view of the device as assembled.

Referring to the drawings by characters 40 of reference 1 indicates a window of the ordinary construction, having slidably mounted therein the usual sash 2. This window is framed in the ordinary manner and provided with the strips 3 which are adapted to 45 retain the sash in its position.

My improved shade support preferably 50 comprises the L-shaped member 4 which is bent as clearly illustrated at 5 to form a rearwardly extending projection which is adapted to be pressed into the groove 55 formed between the strip 3 and the window casing. The other arm of the L-shaped

member indicated by the numeral 6 is preferably provided with the upturned portions 7 which extend substantially throughout the 55 entire length of the member 6 and are adapted to form guides, the use of which will be more fully hereinafter described. Intermediate the ends of the arms 6 of the L-shaped member I preferably provide an aperture 60 through which the bolt 8 is adapted to extend.

Coöoperating with the L-shaped member I preferably provide a suitable member 9 which is reduced adjacent one end, as clearly 65 shown at 10, and terminates in the upstanding portion 11. This upstanding portion is preferably provided with an aperture as indicated at 12 for the reception of the end of the shade roller when the device is in position. The end 13 of the coöperating member 9, opposite the reduced end, is preferably provided with the longitudinally extending slot 14 through which the bolt 8 is adapted to extend. Extending laterally from the 70 side walls of the portion 13 I preferably provide the guide members 15 which are adapted to project into the grooves formed by the upturned members 7 and hold the coöperating member 9 firmly in position. 80

In operation it will be clearly seen upon referring to the drawings that my improved device is secured to the window by forcing the rearwardly extending member 5 into the opening between the strip 3 and the 85 window frame. When it is desired to place a shade roller in position it is obvious that by loosening the bolt 8, the coöperating member 9 may be longitudinally adjusted with relation to the member 4 and in that 90 way shades of varying widths may be used.

While in the foregoing I have shown and described the preferred embodiment of my invention, I wish it to be understood that I may change the specific arrangement of 95 parts without in any way departing from the spirit and scope of my invention.

What I claim is:—

A shade bracket including an attaching element, a supporting element, said attaching element comprising a horizontal base plate arranged to extend between the upper side of a window frame and the upper molding strip thereof, an upstanding arm on the 100

base plate, said arm projecting at right angles thereto, a laterally extending arm formed at the upper end of the upstanding arm, and means to secure the supporting element to the attaching element, the base plate being arranged to be inserted between the window frame and the upper molding strip at any desired point intermediate its

length to accommodate shade rollers varying in length.

In testimony whereof I affix my signature in presence of two witnesses.

MAX E. HERTWIG.
